200,424

COMBINED LAWN EDGER FRAME AND SUPPORTING WHEELS THEREFOR

Marvin W. Bayless, Sr., Fairborn, Ohio, assignor to The
Huffman Manufacturing Company, Dayton, Ohio, a
corporation of Ohio

Filed Mar. 10, 1964, Ser. No. 78,953

Term of patent 14 years

(Cl. D40—1)

FIG-4

FIG-5

FIG. 1 is a perspective view of a combined lawn edger frame and supporting wheels therefor showing my new design;

FIG. 2 is a side elevational view of my design;

FIG. 3 is a top plan view thereof;

FIG. 4 is a front elevation view of my design; and

FIG. 5 is a fragmentary elevational view of the handle portion of the combined lawn edger frame and supporting wheels therefor as viewed along the line 5—5 of FIG. 2.

The portions shown in broken lines in FIG. 1 are included for illustrative purposes only.

I claim:

The ornamental design for a combined lawn edger frame and supporting wheels therefor, substantially as shown and described.
